UNITED STATES PATENT OFFICE

2,575,406

BREAST LEAF SPLITTING MACHINE

Robert L. Bradley, Beverly, Mass., assignor to
United Shoe Machinery Corporation, Flemington, N. J., a corporation of New Jersey

Application June 21, 1949, Serial No. 100,371

15 Claims. (Cl. 12—16.5)

1

This invention relates to splitting machines and is illustrated as embodied in a machine for splitting heel breast covering flaps from outsoles of shoes.

It is an object of the present invention to provide an improved machine of the well-known Empire type for quickly and effectively splitting without adjustment heel breast covering flaps from shank reduced outsoles of different sizes, irrespective of the angles of the shank reducing bevels on the outsoles or the lengthwise extent of said bevels.

With the above object in view, the illustrative machine, in accordance with a feature of the present invention, comprises a support for a piece of flexible material of nonuniform thickness, such as an outsole which has been shank reduced; a resilient bracer, herein shown as a pair of leaf springs mounted upon the support and arranged between the beveled margins of the outsole and the support; a presser member; a knife; and means for effecting relative movement of the support on the one hand and the presser member, the knife and the bracer on the other hand to effect splitting of said material.

The illustrative machine is of substantially the same construction as a machine disclosed in United States Letters Patent No. 2,118,825, granted May 31, 1938 on an application filed in the name of Thomas H. Seely, the support of the machine having the form of a table which is yieldable and the presser member and the knife being mounted on a carriage movable over the table to effect the splitting of heel breast covering flaps from the outsoles presented successively upon the table. In order effectively to support the lateral margins of shank-reduced outsoles of different sizes, the leaf springs are upwardly bowed and are mounted for sliding movement over the table and lengthwise of the outsole in response to movement of and at the same speed as the carriage, said springs serving effectively to support progressively the beveled lateral margins of the outsole being split against the action of the presser member which as above explained is mounted upon the carriage and moves lengthwise of the outsole together with the splitting knife.

In the drawings,

Fig. 1 is a plan view, partly broken away and partly in section, of the illustrative machine;

Fig. 2 is a longitudinal vertical section on line II—II of Fig. 1;

Fig. 3 is a transverse vertical section on line III—III of Fig. 2;

2

Fig. 4 is a side elevation, partly in section, of the rear portion of the illustrative machine;

Fig. 5 is a section on line V—V of Fig. 3 showing, during the splitting operation, the relative positions of the various machine parts operating upon the outsole;

Figs. 6 and 7 show an enlarged section through a sole, shown on an upper portion of line III—III of Fig. 2, and taken during two different portions of the flap splitting operation; and

Fig. 8 shows in perspective an outsole which has been operated upon by the illustrative machine.

The illustrative machine is described with reference to splitting from an outsole 22, which has been shank reduced by beveling cuts 24 (Figs. 6 and 8), a heel-breast-covering flap 25 (Figs. 5 and 8), the central base portion of which is thicker than the remaining uniformly thick portion thereof. The flap 25 formed by the present machine may be reinforced at selected localities as above described or may be of uniform thickness throughout its entire extent. The beveling cuts 24 formed on the outsole 22 during the shank-reducing operation usually extend forward to a break line 26 (Fig. 8) of the outsole and rearward at least to a heel-breast line 28 of the outsole, it being common practice, in view of the fact that the margin at the heel end of the outsole is removed during a subsequent heel-seat-fitting operation, to extend the beveling cuts 24 to the rear end of the outsole as indicated by dash lines 30 (Fig. 8) or to terminate the beveling cuts anywhere rearward of said heel-breast line.

In order effectively to split the heel-breast covering flap 25 from the outsole 22 in a machine which is of the general type disclosed in said Patent No. 2,118,825 and on which the present machine is an improvement, a work support or table 32 is provided with flexible leaf springs or bracers 40 hereinafter described for supporting or bracing the lateral margins of the outsole positioned on the table against the action of a presser member 34 and a knife 36 (Figs. 1, 2 and 5) which are mounted upon a carriage 38 movable forward and then back in a predetermined rectilinear path over the table. During the splitting operation, the flexible leaf springs or bracers 40 travel along the table 32 beneath the lateral margins of the outsole 22 mounted upon said table and serve effectively to brace said margins against the action of the presser member 34 and the knife 36 irrespective of the size of the outsole and irrespective of the

angle or the lengthwise extent of the beveling cuts 24 on said outsole.

The table 32 which is U-shaped in transverse section, as best illustrated in Fig. 3, is mounted upon a table carrier 42 (Figs. 2 and 3) supported by a plurality of coil springs 44, the lower ends of which are housed in recesses 46 in a base 48 of the machine and the upper ends of which are centered by retaining studs 50 fitting in bores 52 of the table carrier 42. Elevation of the table carrier 42 under the action of the springs 44 is limited by a plurality of threaded studs 54 (Fig. 2) which are screwed into the base 48, have shanks mounted for sliding movement in bores of the table carrier 42, and are provided with heads arranged in sockets 56 in the carrier. Slidable in inclined slots 58 formed in vertically disposed flanges of the table 32 are blocks 60 mounted upon rods 62 secured to the table carrier 42. As will be explained later, the work table 32 may be moved into different heightwise operating positions upon the table carrier 42 by moving it forward or rearward thereon.

Thus, to enable the table to be pushed up these slots when the machine is at rest and during the splitting of a flap, a header 66 (Figs. 1, 2 and 4) is adjustably secured to the rear end of it by screws 68 (Fig. 1) which are threaded into said table and pass-through elongated slots 70 in the header. Secured by a setscrew 74 (Fig. 2) to the header 66, which may be considered as constituting part of the work table 32, is a pin 76 (Figs. 1, 2 and 4) carrying a cam roll 78 which, when the machine is in its rest position, is engaged by a rotatable segment cam 80 secured to the top of a driven crank 108, to hold the table 32 in a raised position upon the carrier 42. The work table 32 is constantly urged rearward by spring thrust mechanism 82 (Fig. 2) which comprises a plunger 84 having its head in engagement with a cross piece of the table carrier 42 and its shank slidingly mounted in a plug 86 threaded into the header 66, a coil spring 88 surrounding the plunger being interposed between the header and the head of the plunger. The segment cam 80 moves out of engagement with the roll 78 when the knife-carrying carriage 38 reaches the forward end of its stroke, with the result that the work support acted on by the spring-pressed plunger 84 slides rearward and downward until a screw 90 (Figs. 2 and 4) threaded into the header 66 engages a face 92 of the base 48.

The carriage 38 is provided with rectilinear V-shaped notches 94 (Fig. 3) which slide along ways 96 formed upon the base 48 of the machine. By depressing the work table 32 at the end of the flap-splitting stroke of the carriage and holding it depressed during retraction of the carriage, the operator is able to remove the outsole from the machine as soon as it has been split. Just before the carriage 38 has completed its return or back movement to rest position, the segment plate 80 again engages the roll 78 and forces the work table 32, against the action of the spring-pressed plunger 84, forward and upward to its raised starting position shown in Fig. 2.

The carriage 38 has a bore 98 (Figs. 2 and 4) for receiving a coupling pin 100 which extends through a bore in a connecting rod 102. The rear end of the connecting rod 102 is pivoted upon a bushing 104 (Fig. 4) mounted upon a threaded bolt 106 which is secured in different operating positions to a rotatable crank plate 108 with its head arranged in an arcuate slot 110 formed in said plate, by a nut 112 threaded onto

the upper end of the bolt. The slot 110 is centered about an axis of rotation 114 of the crank plate 108 and accordingly the carriage 38 is always moved in a path of a fixed extent. It will be noted, however, that the starting position of the carriage 38 may be varied in accordance with the adjustment of the bolt 106 along the slot 110 but the carriage is always moved forward to the same position.

Pivotedly mounted upon the crank plate 108 is a pawl 116 which is normally urged downward by a leaf spring 118 secured to the plate. When the machine is at rest the pawl 116 is held in a raised position against the action of the spring 118 by a cam 120 which forms part of a swinging unit 122 pivotally mounted upon a pin 124 supported by the base 48. A spindle 126 which is formed integral with the crank plate 108 fits rotatably in a bushing 128 secured in a cylindrical bore of the base 48. A cap 130, which is secured to the lower end of the spindle and underlies the bushing 128, holds it against elevation therein. A worm gear 134, integral with a sleeve 132, is rotatably mounted upon the bushing 128 meshing with a worm 136 forming part of a drive shaft 138 rotatably mounted in the base 48 and driven continuously by a pulley 140. The sleeve 132 is provided with an upper flange having three circumferentially spaced slots 142 (only one shown) formed therein. A treadle (not shown) is connected through a cable 144 to a depending arm 143 of the swinging unit 122 which may be rocked against the action of a spring 150 for causing the machine to operate and which when the treadle is released is moved by the spring to the position shown in Fig. 4 to effect the stopping of the machine. The sleeve 132 is continuously rotated and when the unit 122 has been swung rearward the pawl 116 is no longer supported by the cam 120 and drops into one of the slots 142 thereby causing the sleeve 132 to drive the crank plate 108 and accordingly the segment cam 80. So long as the treadle is depressed the unit 122 is held in its rearward position and the machine will continue to operate. When the unit 122 is rocked to its forward position by the action of the spring 150, however, the pawl 116, as it is engaged by the cam 120, is raised out of the slot 142 of the sleeve 132. At the same time a slotted block 152 of the unit 122 is engaged by a depending pin 154 of the crank plate 108 to prevent further rotation of said plate. The crank plate 108 and accordingly the segment cam 80 are thus held stationary until the unit 122 is again rocked rearward by depression of the treadle.

The work support or table 32 comprises a plate 156 adjustably secured to the main body of the support by screws 158 (Fig. 1) and a median block 160 which is secured by screws 162 to said plate and has rows of rigid prongs 164 on which the median portion of the outsole 22 is impaled during the flap splitting operation. Secured by screws 159 (Fig. 1) to the forward end of the plate 156 is a block 161 (Figs. 1 and 2) in which is rotatably mounted a manually operated crank 163 threaded into a main portion of the work support or table 32. After releasing the screws 158 the plate 156 may be moved into different longitudinally adjusted positions with relation to the main portion of the work support or table 32 by rotating the crank 163, thereby adjusting the machine to vary the length of the flap split from the outsole as explained in detail in said Patent No. 2,118,825.

In order to insure that the beveled margins

of the outsole 22 shall be effectively supported during the flap splitting operation there is mounted upon the table 32 the above-mentioned outsole margin supporting leaf springs or bracers 40 which are bowed upwardly and are slidable lengthwise of the flap along flap upper surfaces 166 of the plate 156. The leaf springs 40, which are movable along said flap surfaces 166, are arranged in opposed relation to the presser member 34, which may be referred to as a drag bar, and immediately ahead of a straight cutting edge 168 (Figs. 1, 2 and 5) of the knife 36 during the flap splitting operation and conform to the portion of the work they engage and insure that the lateral margins of the outsole shall be effectively supported against the action of the presser member so that the lateral margins of the flap shall be of uniform thickness. The splitting knife 36 is secured to the carriage 38 by a pair of cooperating stud screws 170 (Fig. 2) and elongated clamping nuts 172 thereon, and a matrix 174 which constitutes part of the presser member 34 and which has trunnions 175 is rotatable in bearings 176 secured to the carriage 38 by screws 178.

The presser member 34 includes a flexible spacer member 180 comprising a pair of spring plates, the lower of which has a trailing edge 181 (Fig. 5), said edge being forced against the outsole 22 during the splitting operation under pressure of the matrix 174. The matrix 174 and the spacer member 180 are supported through a bracket 182 which is mounted for swinging movement together with a rod 184 eccentrically fulcrumed in bores 186 (Fig. 1) of the carriage 38. The bracket 182 is constantly urged forward to an idle position shown in Figs. 1 and 2 against a vertically disposed end or shoulder 188 (Fig. 1) of a slot in a bar 190 pivotally mounted at its rear end on the carriage 38, by a spring-pressed plunger 192 which is slidable in a bore 193 of the carriage and has its rear end attached to a spring 194 the forward end of which is attached to the carriage, such mechanism being similar to corresponding mechanism disclosed in the above-mentioned Patent No. 2,118,325.

As the cycle of the machine progresses the bracket 182 is swung counter-clockwise as viewed in Fig. 2 against the action of the spring-pressed plunger 192 until the matrix 174 and the spacer member 180 assume, as illustrated in Fig. 5, their operating positions adjacent to the cutting edge 168 of the knife 36, said positions being determined by the engagement of the bracket with a face 196 (Fig. 1) of the carriage.

The illustrative machine is adapted to form flaps 25 which are of uniform thickness or to form flaps which are reinforced at selected localities and have, for example, bullet-shaped reinforcements 198 at their inner median base portions. The reinforcement 198 is formed by rotating the matrix 174 into different positions about an axis of rotation 200 (Figs. 2 and 5) of the matrix during the forward splitting stroke of the carriage 38.

The rotation of the matrix 174 about the axis 200 during the splitting stroke of the carriage 38 is effected upon rotation of an arm 202 (Figs. 1 and 2) which is secured to one of the trunnions 175 and is operatively connected by a link 204 to a lever 206, said lever being pivoted upon a pin 207 secured to the carriage 38 and being operated by a cam follower 208 (Figs. 1, 2 and 4) movable along a cam 209 (Fig. 1) mounted on the

base 48. Since the mechanism for operating the matrix 174 during the flap splitting operation to produce a flap reinforced at selected localities is disclosed in detail in said Letters Patent No. 2,118,325 and has little if any bearing on the present invention such mechanism need not be further described herein.

The outsole 22 is positioned lengthwise upon the table 32 with its rear end in engagement with a bifurcated gage 210 (Figs. 1 and 2) which initially extends a substantial distance above the plate 156 of the table and which during forward movement of the carriage 38 over the plate is depressed by a pair of plows 212 (Fig. 2) which are secured to the carriage. The outsole 22 is manually positioned widthwise upon the plate 156.

The leaf springs or bracers 40 are riveted to slides 216 which carry rolls 218 slidable in elongated guideways 220 (Figs. 1 and 2) of bars 222 which are secured by screws 224 (Fig. 1) to the carriage 38. Mounted for adjustment into different operative positions lengthwise of the bars 222 are abutments 226 which comprise upper and lower portions and are secured to each other and to the bars 222 by screws 230.

The abutments 226 are constructed and arranged to move the slides 216 rearward in response to rearward or retractive movement of the carriage 38 and are so positioned that when the carriage comes to rest the leaf springs 40 attached to said slides are positioned just forward of the back gage 210. As will appear later, the leaf springs 40 are actuated forward as the cutting edge 168 of the knife 36 starts to split the flap from the outsole. The rear ends of the guideways 220 after a substantial lost motion engage the rolls 218 to move the slides 216 forward in response to forward movement of the carriage 38, the construction and arrangement being such that, during the forward flap forming movement of the carriage, the trailing edge 181 of the lower plate of the spacer member 180 in order effectively to control the work is arranged approximately above the rear ends of the leaf springs 40 (Fig. 5). The inner edges of the leaf springs rest upon and slide forward over the flat surfaces 166 of the plate 156 at the same rate that the carriage 38 is moved over said plate.

As the bowed leaf springs 40 slide along the plate 156 in response to forward movement of the carriage 38 they are depressed by the outsole 22 acted upon by the presser member 34 by reason of their inner edges being free to slide transversely of the table under pressure of the outsole, said leaf springs conforming to the outsole and effectively supporting the lateral margins of the outsole against the presser member irrespective of the angle or the length of bevel on the outsole or the size of said outsole. Since the leaf springs 40 assist the table 32 in supporting the outsole they may be considered as part of the table.

The operation of the machine is as follows. The operator places the outsole 22 upon the table 32, said outsole being centralized manually and being positioned lengthwise upon the table by the engagement of the rear end of the outsole with the gage 210. The operator, while gripping the toe end of the outsole and holding the outsole against the gage, depresses the treadle (not shown) causing the cable 144 to be drawn forward and hence, through the mechanism above described, causing the operating plate 108 to be rotated to effect forward movement of the

carriage 38 over the table 32 to split the flap 25 from the outsole. As the carriage 38 moves forward preparatory to splitting the outsole the presser member 34 is swung counterclockwise as viewed in Fig. 2, thereby forcing the outsole against the table 32 and depressing said table and its carrier 42 against the action of the springs 44.

As soon as the carriage 38 starts to move toward its retracted position the table 32 drops down the slots 58 to its lowered position on the support carrier 42 and the presser member 34 swings to its position shown in Fig. 2 away from the knife 36 which is fixed to the carriage, thereby enabling the operator to remove the outsole from the machine as soon as it has been split. When the operator removes his foot from the treadle after starting the machine, the machine after the completion of one cycle comes to rest. A skillful operator sometimes retains his foot on the treadle with the result that the machine moves continuously through successive cycles, the outsoles being presented to and removed from the machine as the machine operates.

Having thus described my invention, what I claim as new and desire to secure by Letters Patent of the United States is:

1. In a splitting machine, a support for a piece of flexible material of nonuniform thickness, a resilient bracer which is mounted upon the support and is arranged between said material and the support, a presser member, a knife, and means for effecting relative movement of the support on the one hand and the presser member, the knife and the bracer on the other hand to effect splitting of said material.

2. In a splitting machine, a yieldable support for a flexible work piece of nonuniform thickness, a leaf spring which is mounted upon the support and is arranged between the work piece and the support, a presser member, a knife, and means for effecting relative movement between the support on the one hand and the presser member, the knife and the leaf spring on the other hand to split from the work piece a flap of uniform thickness.

3. In a splitting machine, a yieldable support for a flexible work piece having margins, portions of which are beveled, resilient bracers which are mounted upon the support and are arranged between the support and opposite lateral margins of the work piece, a presser member and a knife, and means for moving the presser member, the knife and the bracers in predetermined paths along the work piece mounted upon the support to effect splitting of the material from the work piece.

4. In a splitting machine, a yieldable support for a work piece having margins, portions of which are beveled, bowed leaf springs which are slidably mounted upon the support and are interposed between the support and opposite lateral margins of the work piece on said support, a presser member and a knife, and means for moving the presser member, the knife and the leaf springs in predetermined paths along the work piece, which is mounted upon the support and is depressed by said presser member and is braced by said springs, to split material from said work piece.

5. In a splitting machine for producing a flap upon stock, a portion of a margin of which is beveled, a yieldable table for supporting said stock, a splitting knife, a presser member arranged to act upon the stock in advance of the

knife and by its position with respect to the table to determine the thickness of the flap produced by said knife, means for causing relative movement between said table on the one hand and said knife and presser member on the other hand to produce said flap, a resilient bracer interposed between the margin of the stock and the table, and means for causing relative movement between the table and the bracer for progressively supporting the beveled portion of the stock in opposition to pressure of said presser member against the stock during the splitting of said stock by the knife.

6. In a flap splitting machine for operating upon outsoles which have been shank reduced, a yieldable table comprising a pronged median portion, a presser bar and a knife movable in predetermined paths over the table, a pair of yieldable bracers which are supported on said table and are arranged at opposite sides of the pronged median portion of the table, and means for moving the presser bar, the knife and the bracers over the table to split, from the heel end of an outsole upon said table, a heel breast covering flap the margins of which are of uniform thickness.

7. In a splitting machine, a yieldable table comprising a median portion having rows of rigid prongs constructed and arranged to be engaged by the central portion of an outsole which has been shank reduced, a pair of conformable bracers arranged at opposite sides of said rows of prongs and normally projecting beyond said prongs, a carriage, a knife and a presser member mounted upon the carriage, means for moving the carriage in a predetermined path lengthwise of the outsole supported by said table to cause the presser member to force the central portion of the outsole progressively against the rows of prongs of the table and to cause the lateral margins of the outsole to be forced against the bracers, said bracers being movable along the opposite sides of said rows of prongs together with the carriage progressively to support the shank reduced portion of the outsole against the action of the presser member and the knife, to cause to be split from the outsole pressed between the presser member on the one hand and the prongs and the bracers on the other hand a flap the margins of which are of uniform thickness.

8. In a splitting machine, a yieldable table for supporting a piece of flexible stock opposite margins of which are of nonuniform thickness, a carriage, a knife, a presser member mounted on the carriage, one or more conformable leaf springs which are interposed between the table and margins of the stock and are slidably supported on the table, and means for imparting to said carriage movement in one direction in a predetermined path and for moving the leaf springs along said table and said stock in response to movement of said carriage in said one direction to split from said stock a flap the lateral margins of which are of uniform thickness.

9. In a splitting machine, a yieldable support for an outsole lateral margins of which are beveled, a carriage, a knife and a presser member which are mounted on the carriage, a pair of resilient members which are slidably mounted upon said support and are engaged by the lateral margins respectively of the outsole, and means for causing relative translatory movement between the support on the one hand and the carriage and the resilient members on the other

hand to cause the presser member to be forced progressively against portions of the outsole which are in advance of the knife and are progressively braced by the support and by said resilient members to cause the knife to split a flap from said outsole.

10. In a flap splitting machine, a yieldable support for an outsole lateral margins of which are beveled, a carriage movable in a translatory path, a knife and a presser member mounted on the carriage, means for moving the carriage in said path with relation to the support, first in one direction from a retracted position to cause a flap to be split from the outsole by the knife and then in an opposite direction to a retracted position, said presser member being constructed and arranged progressively to engage the outsole mounted upon said support in advance of the knife during movement of the carriage and to control by its pressure against said outsole the thickness of the flap split from the outsole, and a pair of leaf springs which are positioned between the support and the lateral margins of the outsole, said leaf springs being movable lengthwise of the outsole together with the carriage and being constructed and arranged progressively to brace the lateral beveled margins of the outsole with substantial pressure against the action of the presser member and the knife during the splitting of said flap.

11. In a splitting machine, a yieldable table for supporting an outsole having beveled shank margins, a carriage, a knife and a drag bar mounted upon the carriage, means for effecting translatory movement of the table and the carriage to cause the outsole to be progressively conformed to the drag bar and to be split by the knife, said table comprising a block having sharp rigid prongs engaged by the median part of the heel end of the outsole, a pair of leaf springs which are arranged at opposite sides of the block and are shaped and arranged to maintain the beveled shank portions of the sole in transverse alignment with the median portion of the sole, and means movable in response to movement of the carriage to move the leaf springs lengthwise of the outsole just ahead of the knife during the splitting operation to insure that the lateral margins of the outsole are forced with proper pressure against the drag bar.

12. In a splitting machine, a yieldable table comprising a block having rigid prongs for supporting the median part of the heel end of an outsole which has been shank reduced, said table comprising leaf springs arranged at opposite sides of the block and constructed and arranged to be engaged by the lateral portions of the outsole, a knife for splitting a heel breast covering flap from the outsole, a presser member constructed and arranged to act upon the outsole in advance of the knife and by its position with respect to the knife to determine the thickness of the flap produced by the action of said knife, and means for effecting relative movement of the table on the one hand and the knife, the presser member and the leaf springs on the other hand to produce said flap.

13. In a splitting machine, a yieldable table for supporting an outsole which has been shank reduced, said table comprising a rigid median portion provided with sharp prongs constructed and

arranged to be engaged by the central part of the heel end portion of the outsole, said table also comprising movable leaf springs which are arranged at opposite sides of said rigid median portion and are constructed and arranged to support the lateral margins of the outsole which is in engagement with the median portion of the table, a carriage, a knife and a presser member mounted upon the carriage, and means for moving the carriage together with the leaf springs over the table to cause said knife to split a heel breast covering flap from the outsole as said outsole is progressively forced against the table by the presser member.

15. 14. In a splitting machine, a yieldable table for supporting an outsole, a carriage, a presser member and a knife mounted on said carriage, said table having a pronged median portion and flat lateral margins, leaf springs which are mounted for sliding movement over the flat lateral margins of the table, said springs having outer edges which are secured against movement laterally of the table and having inner edges which engage the table and are free to slide transversely of the table when pressure is applied to the springs, means for moving the carriage in a predetermined path lengthwise of the table, and means movable in response to said movement of the carriage for sliding the leaf springs lengthwise and along opposite sides of said table at the same speed as the carriage is moved lengthwise of the table to cause said springs progressively to support lateral portions of the outsole, movement of the carriage lengthwise of the table being effective to cause the presser member to force the outsole against the pronged median portion of the table and to force the lateral portions of the outsole against the springs and to depress the table and also to cause the knife to split the outsole controlled by the presser member, said pronged median portion of the table and the leaf springs.

15. In a splitting machine, a yieldable table for supporting an outsole opposite lateral margins of which are of nonuniform thickness, a carriage, a knife, a presser member mounted on the carriage, one or more conformable leaf springs which are interposed between the table and the margins of the outsole and are slidably supported on the table, means for moving said carriage in a predetermined path, and means operatively connected to the carriage for moving in response to movement of the carriage the leaf springs along a portion of said path with lost motion with relation to the carriage, said carriage when moved together with the presser member in one direction in said path causing the knife to split from the outsole engaged at opposite sides by the presser member on the one hand and the table and the leaf springs on the other hand a heel breast covering flap the lateral margins of which are of uniform thickness.

ROBERT L. BRADLEY.
